UNITED STATES PATENT OFFICE.

CHARLES W. WARE, OF ROSENDALE, MISSOURI.

SCREEN OR RIDDLE CLEANER.

Application filed September 6, 1923. Serial No. 661,218.

To all whom it may concern:

Be it known that I, CHARLES W. WARE, a citizen of the United States, and a resident of Rosendale, county of Andrew, State of Missouri, have invented a certain new and 5 useful Improvement in Screen or Riddle Cleaners, of which the following is a complete specification.

The present invention relates to screen or riddle cleaning devices, and aims to provide 10 an improved brush mechanism adapted for the cleaning of shaker or reciprocating screens or riddles, such as are commonly used in the separators of threshing machines.

For embodying the present improvements, 15 I have devised a cleaning mechanism which comprises a set of brushes adapted for travelling engagement with the screen surfaces, and the drive for the brushes is so arranged as to be actuated from that mechanism 20 which operates the screen or riddle box, and preferably operates to impart an intermittent travelling movement to the brushes.

A further object of the invention is to 25 devise an improved form of brush, in which the bristles are of stiff material, preferably steel, and also preferably of angular form and carried so as to be presented in a direction approaching that in which the brushes are travelling, thereby increasing the efficiency 30 of the cleaning action and also enabling the bristles of the brushes to exert an effective self-cleaning action, thus preventing any clogging of either the screens or brushes.

35 With the foregoing general objects in view, the invention will now be described by reference to the accompanying drawing, in which is illustrated one practical form of construction for embodying the proposed improvements, after which those features deemed to be novel will be particularly set forth in claims.

In the drawing—

40 Figure 1 is a side elevation illustrating a portion of a separator equipped with a screen-cleaning device embodying the present invention;

45 Figure 2 is a horizontal sectional view, representing a section taken on a line II—II 50 of Figure 1;

55 Figure 3 is an enlarged vertical sectional view, representing a section taken on a line III—III of Figure 2; and

Figure 4 is a sectional detailed view of one 55 of the brush members.

Referring now to the drawing in detail, this illustrates the invention in connection with a separator construction such as commonly used in threshing machines and comprises a screen box 5 supported for shaking or reciprocating motion by means of hangers 6 pivotally connected, as indicated at 7, to the frame 8 of the machine. The necessary reciprocating motion is imparted to the box 60 5 in the usual manner by means of operating connections 9 from a crank shaft 10, designed to be rotated through the medium of drive connections of the usual type.

The interior of the box 5 is provided with 70 the usual screens 12, 14, angularly arranged and spaced apart as illustrated in Figure 3. Various methods have been devised for cleaning these screens which, in practice, become more or less clogged with material, 75 thereby interfering with the screening operation. For more effectively accomplishing this cleaning function, I have devised brush members having an intermittent movement 80 and of such a type as to have a self-cleaning action in addition to thoroughly cleaning the screens. For this purpose I provide a plurality of travelling brush members, two being illustrated, and each comprising a transverse cross bar 16 carrying brush heads 85 17 provided with a set of steel bristles 18 of U-shaped or staple form having their intermediate portions embedded in and retained by the brush heads 17, the latter being preferably of resilient, flexible material, such as 90 leather. The free projecting ends of the bristles 18 are preferably of somewhat angular form, so that the extremities of the bristles may be presented in the direction of travel of the brushes. The ends of the cross 95 bar 16 are attached to endless conveyor chains 20 operating around sprocket wheels 21, 22, carried by shafts 23 and 24, respectively, which are journaled in the sides of the box 5, the arrangement of these shafts 100 and the relative sizes of the sprocket wheels being such that when one of the brush members is travelling in engagement with the under face of the upper screen 12, the other brush member will be travelling in engagement with the upper face of the lower screen 14 and in the opposite direction. One of the ends of the shaft 24 is provided with a ratchet wheel 26 adapted for engagement 105 with a tooth 27 on the end portion of an arm 28, the lower end of which is fulcrumed, as indicated at 29, to a fixed bracket 30 carried

by the machine frame 8. A coil spring 32 maintains the arm 28 with its tooth 27 yieldingly engaged with the wheel 26.

By means of this construction, it is apparent that the usual reciprocating motion imparted to the box 5 will cause the wheel 26 to be operated, or rotated, one tooth at a time, by its engagement with the tooth 27 of the arm 28, any reverse movement of the wheel being prevented by a spring-actuated pawl 34 carried by the box 5 adjacent to said wheel. Obviously, such intermittent rotation of wheel 26 will produce a corresponding intermittent travel of the conveyor chains 29 and the brushes carried thereby. This intermittent movement of the brushes is that best adapted for producing the most efficient cleaning action, without involving any clogging of the meshes of the screen, and in this movement of the brushes the bristles 18 are jabbed into the meshes of the screen, in contrast to the wiping movement with which the brushes are commonly carried across the screen. In the present construction, the bristles are jabbed into the screen, which gouges out any clogging material, and as the brush head 17 moves on, the bristles are caught in the screen meshes, and then released, thereby effectually freeing the bristles of any material which may be clinging thereto. Thus the brushes are of a character adapted to thoroughly clean the material from the screens and also to exert a constant self-cleaning function during the travel of the brushes.

The improved cleaning device is adapted for use with any form of separator apparatus employing movable screens from which the desired intermittent movement may be imparted to the traveling brushes. While I have illustrated what represents a practical

form of construction for the device, I desire not to be limited to the specific form shown nor to the specific type of drive connection between the screen box and brushes, but reserve the right to make all such changes and modifications as may fairly fall within the scope of the appended claims. 45

What I claim is:

1. Apparatus of the character described, 50 comprising a reciprocating screen, an endless conveyor device traveling parallel with said screen, a brush carried by said conveyor device in engagement with the screen, and means actuated by the movement of the 55 screen for producing intermittent travel of said conveyor device.

2. Apparatus of the character described, 60 comprising a reciprocating screen, an endless conveyor device traveling parallel with said screen, a brush carried by said conveyor device in engagement with the screen, a shaft acting to drive said conveyor device and provided with a ratchet wheel, and a toothed member supported independently of said 65 screen and in engagement with said wheel for intermittently actuating the latter in response to the reciprocations of the screen.

3. Apparatus of the character described 70 comprising a reciprocating separator member, a pair of spaced screens carried by said member, an endless conveyor device provided with cleaning brushes traveling in alternate engagement with the opposed faces of said screens, and means actuated by the 75 movement of said reciprocating member for producing intermittent travel of said conveyor device.

In witness whereof I hereunto affix my signature.

CHARLES W. WARE.
